SWITCH

George J. Reisinger, Jr., Schenectady, N. Y.

Application July 9, 1931, Serial No. 549,753

3 Claims. (Cl. 206—87)

My invention relates generally to switches for use in normally closed circuits, such as normally closed alarm circuits, and an important object of my invention is to provide a simple and efficient and quick-acting switch of the character indicated which when the alarm circuit, such as a thermostatic fire alarm circuit, is broken, will immediately close another circuit for energizing an alarm device.

Another important object of my invention is to provide in a structure of the character indicated above manual means for quickly and accurately resetting the switch after operation thereof consequent upon a break in the alarm circuit.

Other objects and advantages of my invention will be apparent from a reading of the following description in connection with the drawing, wherein for purposes of illustration I have shown a preferred embodiment of my invention.

In the drawing:—

Figure 1 is a side elevational view of the embodiment showing the same in closed position.

Figure 2 is a view similar to Figure 1 showing the embodiment in open position.

Figure 3 is a transverse vertical sectional view taken through the central part of Figure 1 and looking toward the right.

Referring in detail to the drawing the numeral 34 refers generally to a suitable flat base on one side of which near one end is fastened the electro-magnet having the protruding core 38 which is in magnetic relation to the magnetically permeable button 40 on the free end of the arm 41 which is of spring metal and has its opposite end lying along the top of and fastened to the generally semi-circular band or clamp 41' which embraces the middle part of a horizontally elongated closed end glass or similar material tube 42 which contains a quantity of mercury 52 and has projecting upwardly from its bottom near the right hand end thereof the pair of spaced contacts 51 which are severally connected to binding posts 53 on the adjacent end of the base 34.

Projecting radially in diametrically opposite positions from the outer side of the band 41' are the screws 44 and 45 which are anchored in different L-shaped supports 43 and 43' which have their foot portions fastened to the top of the base as shown in the drawing near the right hand end of the base.

The screws 44 and 45 have their ends pivotally socketed in corresponding depressions in the outer sides of the band 41' whereby the tube 42

carrying the arm 41 is free to pivot on an axis lying in a horizontal plane transverse of the base 34.

Journaled through the lower portion of the supports 43 and 43' is the horizontal part 48 of the resetting device 47, which has on its upper end the horizontal extension 58 and on its opposite end the operating knob 49. A stop pin 46 is located on the support 43 above the screw 44 and in such a position that the resetting device 10 will engage the same in an extreme right hand position and be thereby prevented from being swung needlessly far in a clockwise direction.

A helical spring 45 is circumscribed on the screw 44 between the standard 43 and the band 41' and is attached to the band and to the standard 43 in such a way that the tube 42 and the arm 41 will be swung in a counterclockwise direction unless forced into the opposite direction by manipulation counter-clockwise of the resetting device, the spring 45 being operative to swing the arm 41 and the tube 42 in the clockwise open direction from the closed position shown in Figure 1 whenever the electro-magnet 38 has become deenergized due to a break in the alarm circuit to which the winding of the electro-magnet 38 is connected.

In resetting the switch from the open position shown in Figure 2, the knob 49 is grasped and rotated counter-clockwise until the arm 58 rests against the underside of the arm 41, the counterclockwise rotation of the resetting device will then be continued until the magnetic button 40 on the free end of the arm 41 has been engaged with the core of the electromagnet, whereupon the arm 35 and hence the tube 42 will be held in the closed left-hand tilted position shown in Figure 1 wherein the quantity of mercury 52 will be in the left-hand end of the tube and entirely out of bridging relation to the contacts 51 in the opposite end of the tube, so that the alarm device or signal will be in a deenergized condition.

Although I have shown and described herein a preferred embodiment of my invention, it is to be definitely understood that I do not desire to limit the application of the invention thereto, and any change or changes may be made in the materials and in the structure and arrangement of the parts, within the spirit of the invention and the scope of the subjoined claims.

Having thus described my invention, what claim as new is:—

1. An electromagnetically operated switch comprising a support, a generally horizontally elongated tube pivoted near its middle on said sup-

- port, a quantity of conductive fluid movably contained by said tube, a pair of contacts within one end only of said tube and arranged to be bridged by said conductive fluid while the said end of the tube is depressed below the horizontal and while the opposite end of the tube is elevated above the horizontal, spring means connected between said support and said tube and normally rotatably urging said tube toward operated position in which the said one end of the tube is depressed, an arm fixed to said tube adjacent its said middle and projecting longitudinally along and above said tube and beyond the said opposite end thereof, a resetting member pivoted on said support and having a part transversely overlying said arm and engageable with the upper side of said arm, said resetting member being arranged to be swung to bring said part down on said arm to rock said arm and said tube from said operative position to the set position in which said opposite end of the tube is depressed and said one end thereof elevated with respect to the horizontal and said fluid is out of bridging relation to said pair of contacts, and electromagnetic holding means holding said arm in the set position, said electromagnetic means being arranged to release said arm upon a change of magnetic flux to permit said spring means to operate said tube into the operated position.
- 30 2. An electromagnetically operated switch comprising a support, a generally horizontally elongated tube pivoted near its middle on said support, a quantity of conductive fluid movably contained by said tube, a pair of contacts within one end only of said tube and arranged to be bridged by said conductive fluid while the said end of the tube is depressed below the horizontal and while the opposite end of the tube is elevated above the horizontal, spring means connected between said support and said tube and normally rotatably urging said tube toward operated position in which the said one end of the tube is depressed, an arm fixed to said tube adjacent its said middle and projecting longitudinally along and above said tube and beyond the said opposite end thereof, a resetting member pivoted on said support and having a part transversely overlying said arm and engageable with the upper side of said arm, said resetting member being arranged to be swung to bring said part down on said arm to rock said arm and said tube from said operative position to the set position in which said opposite end of the tube is depressed and said one end thereof elevated with respect to the horizontal and said fluid is out of bridging relation to said pair of contacts, and electromagnetic holding means holding said arm in the set position, said electromagnetic means being arranged to release said arm upon a change of magnetic flux to permit said spring means to operate said tube into the operated position, said electromagnetic holding means including a member flexibly mounted adjacent the free end of said arm and having a notch normally receiving and holding said free end of the arm to retain the arm and said tube in the set position, and electromagnet means for flexing said member away from and causing said member to release said arm.
